UNITED STATES PATENT OFFICE.

BRUNO THOMAS, OF SEATTLE, WASHINGTON.

FURNACE FOR ELECTRICAL OXIDIZATION OF GASES.

1,359,933.

Specification of Letters Patent. Patented Nov. 23, 1920.

Application filed July 18, 1917. Serial No. 181,197.

To all whom it may concern:

Be it known that I, BRUNO THOMAS, a citizen of the United States, and resident of the city of Seattle, county of King, and State of Washington, have invented certain new and useful Improvements in Furnaces for Electrical Oxidization of Gases, of which the following is a specification.

My invention relates to furnaces in which 10 oxidation of gases is produced by means of an electric arc. One of the principal uses for which this furnace is designed is for the fixation of atmospheric nitrogen. It is, however, to be understood that while this is referred to as the principal use of the furnace, it may be employed for any other purpose to which it is adapted.

The object of my invention is to improve upon the features of construction of such 20 furnace and to thereby obtain a higher efficiency of action. To secure this result I have modified the design of the furnace in such way as it is believed will better subject the air to the action of the arc and at the 25 same time will rapidly cool the gases after having been subjected to the arc, thereby preventing dissociation of the gases which have been combined under the influence of the arc.

30 The novel features of my invention may be determined from an inspection of the accompanying drawings and the following specification, and the features which are believed to be patentable will be defined by the 35 claims.

Figures 1 and 2 are, respectively, vertical section and transverse horizontal section of one type of construction.

Figs. 3 and 4 are, respectively, vertical section and horizontal section, the latter upon the line 4—4 of Fig. 3, showing a slightly modified construction.

Figs. 5 and 6, 7 and 8, and 9 and 10, taken in pairs are, respectively, vertical sections 45 and horizontal sections of modified constructions of furnace.

In the form of construction shown in Figs. 1 and 2, 1 represents the furnace chamber, or that in which the arc is produced, 2 represents the outer electrode and 3 the inner electrode. The outer electrode is here shown as an annulus having its upper surface as a frustum of a cone. This electrode is preferably made hollow and water

is circulated through this by means of the 55 pipes 4, 4.

The central electrode 3 is made hollow and is located within the outer electrode 2. In the construction shown in Figs. 1 and 2, the cooling of the inner electrode is by means 60 of a current of air which is supplied thereto through the pipe 32 which forms the support for the electrode.

The electrode 3 is in the form of two separated disks 30 which are joined by wings or 65 vanes 31, which are preferably given a spiral character, so that the air in discharging is given a tangential impulse, thereby producing a whirling movement which throws the air out against the outer, water cooled walls 70 of the chamber 1. The arc is formed between the outer edge of the electrode 3 and the conical upper surface of the electrode 2. The air issuing from the periphery of the inner electrode passes through this arc and 75 is then immediately thrown out against the water cooled walls of the furnace chamber. In consequence, it is quickly cooled after being subjected to the combining action of the electric arc.

80 The hole through the base 15, upon which the furnace is mounted and through which the pipe 32 carrying the inner electrode passes, is larger than the pipe, thus leaving an annular passage 16. This communicates 85 with the chamber 17 formed in the base 15, which chamber is substantially concentric with the opening 16. The air supplied thereto is introduced to this chamber through a pipe 18, which pipe may be and preferably 90 is, placed so as to be substantially tangential to the chamber 17, thereby giving the air a rotative effect in this chamber, which effect persists when it is discharged between the electrodes.

95 The construction shown in Figs. 3 and 4 is, in the main, similar to that of Figs. 1 and 2. The inner electrode 34 is, however, so constructed as to be water cooled and the air is all introduced around the supporting pipe 100 or stem 32 and none of it through the electrode. The electrode 34 is in the form of a thick hollow disk and within this is placed a plate disk 5, which has a hole centrally thereof which connects with a pipe 50, which 105 extends downward through the pipe 32 and through which water is supplied. The water which is discharged at the upper surface of

the disk 5 flows about the outer edge thereof, which outer edge is spaced inward from the wall of the electrode and thence down and through the pipe 32 and outside of the pipe 50.

In the construction shown in Figs. 5 and 6, the inner electrode 35 is of cylindrical character and hollow. The outer electrode 20 is in the form of a ring or annulus which surrounds the inner electrode and is spaced therefrom, thus forming a channel for the passage of the air. Both of these are water cooled. The channel 16, through which the air enters the furnace chamber, has at its lower end a set of angularly placed vanes or blades 6 which give the entering air a whirling movement. The arc, when first formed, is in the passage 16, but the current of air entering therethrough will blow the arc out into the chamber 1.

The furnace construction shown in Figs. 7 and 8 is like that shown in Figs. 5 and 6, with the exception that the two electrodes 20 and 35 are made of the same height, whereas, in Figs. 5 and 6, the inner electrode is considerably higher than the outer.

The construction shown in Figs. 9 and 10 is similar to that shown in the two preceding forms with the exception that the inner electrode is of but half the height of the outer. In these two figures the position of the entering air has been shown as tangential to the air supply chamber 36. Otherwise the construction is the same as in the two preceding forms.

By the construction of furnace as herein described the electrodes may be kept cool and the air immediately after being supplied to the influence of the arc, is brought into direct contact with the cooling surfaces of the furnace wall. At the same time the cooling of the electrodes assists materially in also cooling the chamber and the gases after treating.

What I claim as my invention is:

1. In a furnace of the character described two concentric electrodes spaced apart to form an annular air inlet passage, and inclined vanes located in said passage to give the incoming air a whirling movement about the axis of the electrodes before entering the arcing chamber.

2. A furnace of the character described

comprising a ring-like outer electrode having a conical inner surface, a complementary electrode positioned within and adjacent the tip of said cone and being hollow and having air discharge openings about its periphery.

3. A furnace of the character described having a ring-like electrode, an inner electrode having a hollow stem passing through the central opening of the other electrode, and means for introducing air through said inner electrode and its stem, said inner electrode having openings about its periphery discharging the air in a general tangential direction.

4. A furnace of the character described having a ring-like electrode, an inner electrode having a stem passing through the central opening of the other electrode, said inner electrode and stem being hollow for the passage of air therethrough, said inner electrode being provided with peripheral openings discharging the air in approximately a tangential direction.

5. A furnace of the type described having two concentric electrodes, the inner electrode being disk shaped and hollow and having spiral vanes therein and peripheral openings, and a hollow stem supporting said inner electrode, whereby a cooling medium may be passed through said electrode.

6. In a furnace of the type described, a ring electrode having a conoidal arcing surface, a complementary electrode within and adjacent the tip of said conoidal surface and leaving an annular gas inlet between the two electrodes and means for supplying the gas to be treated to said inlet with a movement of rotation about the axis of said inlet opening.

7. In a furnace of the type described, a ring electrode having an inner conoidal surface, a complementary inner electrode within the opening of the ring electrode, a preliminary gas receiving chamber into which the gas is introduced to give it a whirling motion, said chamber having a central gas supply connection with the annular space between the electrodes.

Signed at Seattle, Washington, this 12th day of July, 1917.

BRUNO THOMAS.
